5 SHEETS—SHEET 3.

A technical line drawing of a mechanical assembly, likely a pump or valve assembly. The drawing is oriented vertically. Key components and their numbers are:

- 1: A small part at the top left.
- 5: A part at the top left.
- 32: A part at the top left.
- 33: A part at the top center.
- 34: A part at the top center.
- 35: A part at the top center.
- 6: A part at the bottom left.
- 11: A part at the bottom left.
- 16: A part at the top right.
- 17: A part at the top right.
- 18: A part at the top right.
- 19: A part at the top right.
- 20: A part at the top right.
- 28: A part at the bottom right.
- 29: A part at the bottom right.
- 30: A part at the bottom right.
- 36: A part at the bottom right.
- 37: A part at the bottom right.
- 40: A part at the bottom right.
- 41: A part at the top left.
- 42: A part at the top right.
- 43: A part at the top right.
- 44: A part at the bottom left.
- 45: A part at the bottom right.
- 46: A part at the bottom right.
- 47: A part at the bottom right.
- 48: A part at the bottom right.
- 49: A part at the bottom right.
- 50: A part at the bottom right.
- 51: A part at the bottom right.
- 52: A part at the bottom right.
- 53: A part at the bottom right.
- 54: A part at the bottom right.
- 55: A part at the bottom right.
- 56: A part at the bottom right.
- 57: A part at the bottom right.
- 58: A part at the bottom right.
- 59: A part at the bottom right.
- 60: A part at the bottom right.
- 61: A part at the bottom right.
- 62: A part at the bottom right.
- 63: A part at the bottom right.
- 64: A part at the bottom right.
- 65: A part at the bottom right.
- 66: A part at the bottom right.
- 67: A part at the bottom right.
- 68: A part at the bottom right.
- 69: A part at the bottom right.
- 70: A part at the bottom right.
- 71: A part at the bottom right.
- 72: A part at the bottom right.
- 73: A part at the bottom right.
- 74: A part at the bottom right.
- 75: A part at the bottom right.
- 76: A part at the bottom right.
- 77: A part at the bottom right.
- 78: A part at the bottom right.
- 79: A part at the bottom right.
- 80: A part at the bottom right.
- 81: A part at the bottom right.
- 82: A part at the bottom right.
- 83: A part at the bottom right.
- 84: A part at the bottom right.
- 85: A part at the bottom right.
- 86: A part at the bottom right.
- 87: A part at the bottom right.
- 88: A part at the bottom right.
- 89: A part at the bottom right.
- 90: A part at the bottom right.
- 91: A part at the bottom right.
- 92: A part at the bottom right.
- 93: A part at the bottom right.
- 94: A part at the bottom right.
- 95: A part at the bottom right.
- 96: A part at the bottom right.
- 97: A part at the bottom right.
- 98: A part at the bottom right.
- 99: A part at the bottom right.
- 100: A part at the bottom right.

UNITED STATES PATENT OFFICE.

THEOCTISTE POLJAKOFF-KOWTUNOFF, OF IJORA, NEAR ST. PETERSBURG, RUSSIA.

VEHICLE WITH AUTOMATIC MOVEMENT OF RAILS.

No. 892,681.

Specification of Letters Patent.

Patented July 7, 1908.

Application filed March 27, 1907. Serial No. 364,893.

To all whom it may concern:

Be it known that I, THEOCTISTE POLJAKOFF-KOWTUNOFF, residing at Ijora, near St. Petersburg, Russia, manufacturer, have 5 invented a new and useful Vehicle with Automatic Movement of Rails, of which the following is a specification, reference being had therein to the accompanying drawings.

This invention relates to a vehicle which 10 is intended for transporting heavy loads, as well as for the installation of sundry machines, performing work with movement from place to place, such as machines for excavating, digging tunnels etc.

15 The automatic movement of rails with the sleepers under the vehicle itself during its travel, without detaining the latter, forms an important feature of my invention. In this way the vehicle travels continuously along 20 rails, which it moves itself and thus making it possible to transport heavy loads on it along soft roads with a comparatively small expenditure of power. The movement of the vehicle is performed with the aid of mechanical or live motive power.

25 On the annexed drawings, Figure I represents a side view of the vehicle; Fig. II, is a plan of the same without the covering; Fig. III is an end view and cross-section; Figs. 30 IV, V, VI, VII and VIII are details of the arrangement.

The vehicle consists of frame 1, tied with cross and longitudinal beams 2 and 3 and resting on axle 4 on which two wheels 5 and 6 35 are rigidly set on the ends. The wheels 5 and 6 have the form of disks with slots, as shown in Fig. IV. The wheels 5 travel along the interior rails 7 and the wheels 6, along the exterior rails 8.

40 In Fig. I the position of the vehicle is shown standing on all the wheels and moving in the direction of the arrow; during further movement the wheels 6 separate from the rails 8 and the travel of the vehicle is continued on wheels 5 along rails 7. The axles 4 have eccentrics 9 (Fig. IV) with two cross-heads each; the eccentrics 9 are fixed on the axles in such a manner, that, when the wheels separate from the axles the cross 45 heads 9 rise and raise the rollers 10, fastened to the longitudinal beams 11. The latter are fastened to the cross beams 12 by flat rods 13 and support the rails 8 on the rollers 15 (Fig. III); thus the rails 8 with the sleepers 16 are raised by the eccentric 9 (Figs. II and VI), connected together with rods 17

(Fig. III). In order that the frame with the rails should have only a vertical movement, the rods 13 travel in guide plates 14, fastened from beneath to the frame 1. As the rails with 60 the sleepers rise the vehicle moves forward and pulls rope 18 (Fig. VI), both ends of which are fastened to the forward end of the vehicle, to the additional beam 19. The end of the rope 18^a surrounds the roller 20, fastened to the sleepers 16 supporting the rails 8, then it surrounds the roller 21, fastened to the beam 19 and finally it surrounds the roller 22, fastened to the sleepers 23, supporting the rails 7 and is then fastened with the 65 aid of a spring with the air buffer 24 to the beam 19. Thus during the travel of the vehicle, while the rails are not raised the spring 24^a is compressed, when the rails 8 rise, however, the rope draws the wheel 20 70 and thus removes the rails to the extent of double the length of the space covered by the vehicle. As a matter of fact, as is seen from Fig. VI during the movement of the vehicle from position A to position B, the wheel 20 75 will pass the double track from position A' into position B'; at the same time the wheels 6 will travel $\frac{1}{4}$ of a turn and will stop lightly on the rails 8 and the wheels 5 will separate from the rails 7. Then the same action will 80 repeat, as described above, and the rails will move in an exactly similar manner, as the roller 20 will be motionless and roller 22, with the rails and sleepers raised, will move from the position A to the position C until 85 the vehicle moves from B to C. The moving ropes are included for the equability of the movement from both sides, as shown in the plan, Fig. II. So that there should not be a difference in the position of the slots and 90 projections between the wheels of the front and rear axles, the wheels are tied together with rods 25 and 26, placed on the fingers at an angle of 45° (Fig. II).

The force of the live motive power is applied directly to the draft hook 27. In the case of mechanical motive power, movement is transmitted to one of the axles, the remaining ones moving with the aid of rods 25 and 26.

95 The peripheral outline of the wheels may be different, in the drawing they are shown with two slots, but may be made with one, three or more. The number of cross-heads on the eccentrics 9 is made according to the number of slots.

100 110 The turning of the vehicle is performed by means of a turn-table consisting of three disks

28, 29 and 30 (Fig. III). In turning, the vehicle stops on the outside rails; the sleepers located under the turn-table separate from the rails by the turning of pawls 31 (Figs. VII and VIII), then, by means of a handle inserted on the square of roller 32, with the aid of gear wheels 33 and 34, roller 35, chain wheel 36 and four chain wheels 37, rotated by chain 38 screws 39 are turned, which when turning in nuts 40, lower the disk 28. When the disk 28 abuts into the sleepers 23, then the upper disks 29 and 30, being fastened to the beams 2 and 3, will raise the whole vehicle with the rails and remaining sleepers to such an extent that the vehicle should turn easily. The turning of the vehicle is performed by hand, the disk 30 rotating on rollers 41 along disk 29. On having made the required turning with the same handle, the vehicle is set down on the rails and then by a further movement of the roller 32 the disk 28 is raised to the previous position; after this the sleepers are put in place and fastened by pawls 31 (Figs. VII and VIII) and the vehicle travels further.

Having thus fully described my invention what I claim is:

1. In a vehicle for running upon and transporting its rails, a vehicle body provided with rotatable axles, separately movable pairs of rails, cams rotated by said axles,

mutilated traction wheels arranged in pairs upon said axles and with the wheels of a pair out of engagement with the pair of rails therefor while the wheels of the other pair are in engagement with rails, and means carried by the vehicle body for moving either pair of rails when not engaged by traction wheels.

2. In a vehicle for running upon and transporting its rails, a vehicle body carrying a turn-table device, separately-movable pairs of rails upon which said vehicle body runs, mutilated traction wheels carried by the vehicle body and running in pairs on the rails, the wheels of either pair being out of engagement with the rails therefor while the wheels of the other pair are in engagement with rails, means carried by the vehicle body for moving either pair of rails when not engaged by the traction wheels, and means for bodily lowering the turn-table to permit the entire vehicle and the pairs of rails to be swung about the axis of the turn-table.

In testimony whereof, I have signed my name to this specification in the presence of two subscribing witnesses.

THEOCTISTE POLJAKOFF-KOWTUNOFF.
